UNITED STATES PATENT OFFICE.

SHEDRICK H. BROWN, OF JERSEY CITY, NEW JERSEY, AND WILLIAM E. MCPHERSON, OF ALBANY, NEW YORK.

BERTH-CURTAIN.

No. 894,810.

Specification of Letters Patent.

Patented Aug. 4, 1908.

Application filed November 22, 1907. Serial No. 403,428.

To all whom it may concern:

Be it known that we, SHEDRICK H. BROWN and WILLIAM E. MCPHERSON, citizens of the United States, residing at Jersey City and Albany, respectively, in the counties of Hudson and Albany, respectively, and States of New Jersey and New York, respectively, have invented certain new and useful Improvements in Berth-Curtains, of which the following is a specification.

This invention comprehends certain new and useful improvements in curtains for the berths of sleeping cars and the like, and the invention has for its object a simple, and effective construction of curtain which will avoid the well known disadvantages that are incident to the use of the laterally separable curtains heretofore usually employed and that will possess, when in use, the characteristic of privacy to the occupant of the berth and will enable the occupant of either the lower or upper berth to readily enter or depart from the berth without interfering with or disturbing the passenger above or below.

With these and other objects in view as will more fully appear as the description proceeds, the invention consists in certain constructions and arrangements of the parts that we shall hereinafter fully describe and claim.

For a full understanding of the invention, reference is to be had to the following description and accompanying drawings, in which:

Figure 1 is a perspective view of the interior of a sleeping car illustrating the application and use of our invention; Fig. 2 is a front elevation of one of the improved berth curtains, part of the upper flap being shown broken away; Figs. 3 and 4 are longitudinal sectional views on the lines 3—3 and 4—4, respectively, of Fig. 2; Figs. 5 and 6 are detail sectional views of the rollers and hangers employed, the ends of the rollers being shown therein; Figs. 7 and 8 are end views of the respective roller hangers; Figs. 9 and 10, are detail side elevations of the end portions of the roller; and, Fig. 11 is a detail front elevation of an auxiliary curtain designed to cover the space between the side edges of the main curtains between the upper berths of two adjacent sections, as illustrated applied in Fig. 1.

For the purposes of illustration only, we have selected the interior of a sleeping car to

set forth clearly the application of our invention, although it is to be understood that the berth curtains are equally applicable for use in connection with steam boats, public state rooms, or in other analogous locations.

In the drawings, the reference letters A, B and C designate three adjacent sections, separated by the stationary lower berth supports D for the lower berths E, and F designates an ordinary hinged bed portion for an upper berth G.

In carrying out our invention, we provide a series of horizontally extending rods 1 above the respective sections, and if desired, we may employ for this purpose the rods that are already installed in the car for the laterally separable hanging curtains or drapery, for by so doing, it is evident that all necessity for any material changes in the interior construction of the cars is avoided. Upon each of the rods 1, roller hangers 2 and 3 are suspended, as clearly illustrated in Fig. 1, each of said hangers being formed at one end with an opening, by which it may be slipped over the end of the rod, and removed therefrom whenever desired. The preferably spring roller 4 for the berth curtain proper, is provided at its ends with gudgeons 4^a; and 4^b, as best seen in Figs. 5, 6, 9 and 10, the gudgeon 4^b being formed with a lug, as shown, so as to fit in the depression in the socket of the hanger 3 to maintain the proper spring action as the roller turns in one direction or the reverse. The spring is not shown, but it is obvious that any of the ordinary spring rollers of the Hartshorn type may be employed.

The curtain 5 is adapted to wind upon the roller 4 in the nature of a shade or blind, and said curtain may be formed of any material sufficiently heavy for the purpose. The curtain 5 is manifestly of a width to extend substantially from one end to the other of the berth section, and is provided at its side edges with buttons 6 or similar fastening devices that are secured to its rear face, as clearly indicated in the drawings. Near its lower corners, the curtain 5 is formed with eyelets or button-holes 7 arranged for detachable engagement with the headed studs 8 secured to the parts D, as best seen in Fig. 1. The buttons or similar male fastening devices 6 are designed for engagement in the button-holes 9 of substantially triangular supplemental curtains 10 that are designed to be hung from

two adjacent rods 1 by double hooks 11 and that are intended to cover the space between the side edges of two adjacent main curtains 5 along the contiguous upper berths G. Each 5 of these supplemental curtains 10 is provided near its lower end with a fastener 12 which may be of the separable stud and socket type, by which it may be secured to the part D. Each of the main curtains 5 is provided with 10 an upper flap 13 and a lower flap 14 designed to register, respectively, with the upper and lower berths of the section. The upper flap 13 is provided with a binding 15 which is preferably secured to its side and lower edges 15 by stitching, as indicated in Fig. 2, and the lower flap 14 is similarly provided with a binding 16. These bindings 15 and 16 are preferably of leather or some material with a greater "body" or stiffness than the main 20 portions of the curtains and their flaps, and the bindings extend over the sides and lower edges of the openings formed by cutting out the flaps, so as to reinforce the openings and give sufficient weight to the flaps and to prevent them from blowing inwardly or outwardly as the case may be. As indicated, 25 the flaps 13 and 14 are integral portions of the curtains.

From the foregoing description in connection with the accompanying drawings, it will be seen that we have provided a very simple and efficient construction of berth curtain, which will have none of the disadvantageous features common to the laterally separable 30 curtains and which may be easily applied and raised or lowered, while in the use of a curtain constructed in accordance with our invention, it is obvious that the occupant of the upper berth or the occupant of the lower 35 berth, may enter or leave his compartment without interfering with, or intruding upon the privacy of his fellow passenger. By the arrangement of the movable hangers 2 and 3, the entire main curtain on its roller may be 40 detached from the hangers and the latter detached from the supporting rods 1 so that all the parts of the curtain may be stored away in the hinged section F when the berths are not in use.

If desired, the curtain or flap for the upper berth may be provided at its lower edge and in the middle with a button, and the upper end of the flap provided with a loop, so that if desired, the flap may be buttoned or looped 45 up, that the occupant of the upper berth may clearly see in the berth.

Having thus described the invention, what is claimed as new is:

1. In a device of the character described, 50 the combination of an elevated support, hangers mounted on said support, a roller journaled in said hangers, and a curtain

mounted on said roller, said curtain being provided with an opening and a flap designed to close said opening. 65

2. In a device of the character described, the combination of an elevated support, hangers adapted to be slipped over the ends of said support and removably mounted thereon, a roller journaled in said hangers, 70 and a curtain mounted on said roller, said curtain being provided with an entrance and egress opening, and a flap designed to close the same.

3. In a device of the character described, 75 the combination of a supporting rod, hangers provided with openings which may be slipped on the ends of said rods, a roller journaled in said hangers, and a curtain mounted on said roller and provided with an entrance and egress opening, and a flap designed to close said opening.

4. In a device of the character described, 80 a curtain provided with an entrance and egress opening and a flap secured to the curtain at the upper edge of the opening and free therefrom along its side and bottom edges, and a binding secured to the side and bottom edges of the flap and designed to extend over the side and bottom margins of the opening. 85

5. In a device of the character described, 90 the combination of a series of curtains spaced from each other at their side edges, and a supplemental curtain adapted to close a portion of the space between the first named 95 curtains, said supplemental curtain being provided at its upper end with hooks, rods supporting the first named curtains and over which the said hooks are designed to take, and means for securing the first named curtains to the supplemental curtain. 100

6. In a device of the character described, 105 the combination of an elevated supporting rod, a vertically movable roller curtain supported by said rod, means for holding the curtain extended, a supplemental curtain adapted to be secured to said rod and projecting beyond the side edge of the first named curtain, and a detachable fastening connection between the two curtains. 110

7. A curtain for the purpose described, provided with upper and lower openings and flaps for the respective openings.

In testimony whereof we affix our signatures in presence of two witnesses.
